UNITED STATES PATENT OFFICE

2,410,509

APPARATUS FOR MAKING GUT STRINGS

Felix Lange, Chicago, Ill., assignor to Carl G. Bjorkman, Chicago, Ill.

Application May 8, 1943, Serial No. 486,184

11 Claims. (Cl. 57—25)

1

In making gut strings for various purposes, in accordance with Bjorkman Patent No. 2,104,730, successive skeins of fine gut strands are strung between successive pairs of hooks, one hook in each pair rotating to twist the skein. The rotating hooks, or spindles as they are more commonly called, are motor driven. The motor is started after all the skeins are strung and is automatically turned off after it has turned the spindles a predetermined number of revolutions. The number of revolutions through which the spindle is turned must be adjustable since the skeins vary widely in length, depending upon their purpose and a short skein must not be twisted as many revolutions as a long skein.

In the Bjorkman apparatus, the spindle-driving gears and a very complicated counter have accounted for an undue proportion of the total cost and maintenance difficulties, even though the remainder of the apparatus has been so inexpensive and trouble free that the apparatus has been eminently satisfactory when considered as a whole.

According to the present invention, the Bjorkman apparatus has been greatly simplified in these points that have been found troublesome. In spite of the fact that experts in the spindle driving art have insisted that the spindles could not be driven by chains and sprockets, a satisfactory chain drive has been worked out. Presumably, the experts thought that a chain could not drive a sprocket properly unless it was wrapped partly around the sprocket, and space limitations did not permit this. Applicant has determined and proved that the chain running across the tops of the sprockets is sufficient, partly perhaps because the load on the spindle is extremely light. Also, according to this invention, a guard is provided for preventing the chain from jumping off the spindles under exceptional influences, although it does not ordinarily touch the chain and hence represents no appreciable wear or friction. It may be noted that one of the great advantages of the chain drive is that with the chain running across the tops of the sprockets, the spindles all rotate in the same direction without the need of immediate reverse gearing or other complications.

The chain drive lends itself admirably to the simplified counter of this invention since the spindle sprockets are driven by a sprocket twice their size with the result that the drive shaft rotates at an ideal speed for the type of counter of this invention.

In the simplified counter of this invention, a

2

single slide is latched in operative position by a handle and is released automatically after an adjustable number of revolutions of the spindles, turning off the motor and at the same time disengaging the drive worm from the counter wheel so that the latter may return to its starting position under the influence of a weight.

Additional advantages and objects of the invention will become apparent from the following description and the drawings, in which

Fig. 1 is a plan view of the apparatus chosen for illustration of this invention;

Fig. 2 is a side elevation of the structure in Fig. 1;

Fig. 3 is a fragmentary end view of the structure showing particularly an elevation of the counter mechanism;

Fig. 4 is a sectional view taken approximately on the line 4—4 of Fig. 3;

Fig. 5 is a view taken approximately on the line 5—5 of Fig. 4;

Fig. 6 is a sectional view taken approximately on the line 6—6 of Fig. 4; and

Fig. 7 is a sectional view taken approximately on the line 7—7 of Fig. 4.

A preferred form of the invention has been chosen for illustration and description, in compliance with section 4888 of the Revised Statutes, but persons skilled in the art will readily perceive other means for accomplishing the same results, and the claims are, therefore, to be construed as broadly as possible, consistent with the prior art.

The invention has been illustrated in connection with a tank 11 adapted to contain a body of water 12 on which the skeins 13 being twisted may float. The skeins are fastened at one end to spindles 14 and at the other end to hooks 16. The hooks 16 are biased away from the spindles 14 either individually, or in the illustrated form, in a group. This biasing applies tension to the skeins as they are being twisted, the tension being determined by the weight of the weights 17 which are connected to the tail bar 18 by ropes 45 or cables running over pulleys. The hooks 16 are carried by the bar 18 in a manner to prevent the hooks from turning.

The skeins 13 each include a number of very fine strands of gut. To convert the skein into a string, it is necessary for it to be twisted to bind the separate strands tightly together. For high quality and particularly for uniformity, it is necessary that the amount of twisting be accurately controlled. Of course, the number of 55 twists will vary proportionately with the length

of the skein and hence it is necessary for the control mechanism to be adjustable.

The twisting is accomplished by rotating the hooks or spindles 14, these being driven by a motor 21. The motor 21 drives shaft 22 through V-belts 23. The shaft 22 carries a pair of sprockets 24 keyed thereto. A double chain 26 runs around these sprockets, which could be considered a double sprocket, and around idler sprockets or a double idler sprocket 27. Between the sprockets 24 and 27 is a series of driven sprockets 28 each of which is keyed to the shaft 29 of one of the spindles 14. These shafts are rotatably journaled in the casing 31 as clearly seen in Fig. 4.

It is commercially necessary for the spindles 14 to be spaced quite closely together so that a relatively large number of them may be within the reach of the operator from the side of the tank 11. To drive the spindles which are thus closely spaced, the sprockets 28 overlap one another as seen in Figs. 5 and 7. Accordingly, there is not room for the chains to run around the sprockets and around intervening idler sprockets so as to have the arcuate engagement with the sprockets generally considered necessary. According to the present invention, the chain merely rests on top of the sprockets as seen best in Fig. 7. A double chain is used so that one half of it may drive the sprockets closer to the skein while the other half drives the sprockets more remote from the skein.

Actual use has demonstrated the fact that this driving connection in which the chain merely rests on top of the sprocket is entirely satisfactory with the small driving load herein involved. Of course, it is important that the teeth of the sprocket be so shaped that they do not exert very much of an upward thrust on the chain by reaction, but conventional sprocket shapes, such as that shown, are satisfactory. In case there might occasionally be some abnormal condition to cause a chain to jump from the sprockets, guard bars 33 are provided extending along the length of the series of sprockets 28. These guard bars are normally spaced along their length from the chain 26 as seen in Fig. 4 so that they do not introduce any friction or any wear. Inspection after long periods of operation of the device have indicated that there is no appreciable wear if any, and so it may be concluded that most of the time the apparatus would function satisfactorily without the guard bar even though it may be highly desirable for preventing occasional trouble.

Sprockets 24 and 27 are substantially larger than sprockets 28 so that the lower run of the chain 26 will fall below sprockets 28. This avoids the possibility of wearing the sprockets by improper engagement between them and the lower run of the chain which would not be seated properly between the teeth of the sprockets.

The casing 31 comprises an oil reservoir, the oil level preferably being below the level of the bottoms of the sprockets 28 but above the level of the bottom of the sprockets 24 and 27. In this way, most of the sprockets rotate entirely in air so that their rotation is not opposed by the oil, but thoroughly lubricated either by the splash from the sprockets 21 or by oil carried by the chain from the lower portion of the casing 31 to the tops of the sprockets. It has been found convenient to have the sprockets 24 and 27 of twice the diameter of the sprockets 28, both so as to permit considerable variation in

the oil level without disturbing the relationship above discussed, and so that the sprockets 28 will rotate twice as fast as the shaft 22. This permits a convenient driving speed for the shaft 22 both from the standpoint of its being driven by the motor 21 and from the standpoint of its driving the counter.

Counter

The shaft 22 is provided with a worm 36 thereon, this worm driving a worm wheel (not shown) which is keyed to shaft 38. Shaft 38 drives a shaft 39 through universal joints 41 telescopically associated. This permits the shaft 39 to be raised and lowered without interfering with its driving relationship with the shaft 38. The shaft 39 is journaled in lugs 42 on slide 43, the slide being slidably mounted on the main counter bracket 44. The slide 43 tends to drop by gravity to the position shown in Fig. 3 in which a worm 46 carried by shaft 39 is out of engagement with a worm wheel 47 which may be called the counter wheel. The slide 43 may be raised by bell crank lever 48 having a handle portion 49. When raised, it may assume the position shown in Fig. 6 in which the worm 46 engages and drives the counter wheel 31. The slide 43 is automatically latched in this position by a latch 51 forming one arm of a bell crank lever pivoted at 52 to the main bracket 44.

The counter wheel 47 has a drum 53 mounted on its hub and keyed thereto. The weight 54 is suspended from a cable 56 wound on the drum 53 so that the weight tends to rotate the counting wheel 31 in a clockwise direction as seen in Fig. 3. The movement of the counter wheel in this direction is limited by a pin 57 carried by the wheel which engages a stop 58 carried by an arm 59 which is fast on shaft 61. A handle 62 is also fast on shaft 61 so that the angular position of the stop 58 about the shaft 61 may be adjusted. The handle 62 may be held in an adjusted position in any suitable manner as by spring detent engagement with an arcuate plate. The plate 63 is preferably calibrated so that the handle 62 may be set to a position corresponding to any given number of turns.

When the handle 49 is shifted to raise the worm 46 into engagement with counter wheel 47, the counter wheel is rotated in a counter-clockwise direction as seen in Fig. 3 so that the pin 57 leaves the stop 58. As the rotation of counter wheel 47 continues, the pin 57 will ultimately strike the arm 64 of the bell crank lever on the other arm of which is found the latch 51. As the pin 57 is further rotated by the counter wheel 47 it depresses the arm 64 and hence releases the latch 51 so that the slide 43 will drop by gravity and disengage worm 46 from counter wheel 47 so that weight 54 will rotate counter wheel 47 back in a clockwise direction until the pin 57 comes to rest against the stop 58, ready to begin another counting operation.

In order that the counter-clockwise movement of the counter wheel 47 may be assimilated to the driving of the spindles 14, provision is made for controlling the driving motor 21 through the slide 43. Thus as the slide 43 is raised to engage the worm 46 with the counter wheel 47 to start the counting operation, the motor 21 will be started to start the operation which is being counted, namely, the rotations of the spindles 14. When the latch 51 releases the slide 43, the motor will be stopped as the spindles will have reached the desired number of rotations.

A convenient form of motor control involves the use of a mercury switch. This switch may be pivoted at 61 as seen best in Figs. 4 and 6 to the main bracket 44 in such a way that its weight will normally tilt it to its "off" position. A pin 68 is carried by slides 43 and disposed to strike the mounting 69 for the mercury switch 66 in such a way as to tilt the mercury switch to the "on" position when the slide 43 is raised. The mercury switch 66 is, of course, connected in the circuit of the motor 21.

The main bracket 44 may be carried by the casing 31 as illustrated in Figs. 4 and 6. Any suitable movement-limiting means may be provided for the various parts, as for example the pin 71 for limiting the movement of the bell crank lever 48. Likewise any suitable springs may be provided although the leaf spring 72 for urging the latch 51 to the latching position is believed to be the only one required.

Separability

It will be observed that the spindle 14 is journaled in the casing 31 and that it extends over the low top 74 of the tank 11 instead of extending through the ends of the tank, as has been the practice in the past. This permits the entire driving and counting unit to be shifted from one tank to another or to be removed to a convenient place for servicing in the rare event that such servicing is necessary.

Separating partitions 76 between the hooks of spindles 14 and the end portion of the skeins may be hinged to the casing 31 or to the tank at 74. These partitions are desired at this position to prevent interference between the loose portions of the skeins where the free ends of the strands project beyond the tying point.

From the foregoing, it is seen that a greatly simplified rotating and counting mechanism is provided for twisting skeins into gut strings. The driving mechanism uses a minimum number of parts, which are standard parts easily obtained. The counter likewise uses very few parts, some of which may be standard, but in spite of its extreme simplicity, it is easily adjustable for any given number of turns. Both units are designed so that they are substantially free from trouble since there is very little that can get out of order except with years of wear.

I claim:

1. Skein winding apparatus including a plurality of closely spaced spindles, each adapted to have one end of a skein secured thereto, a sprocket on each spindle with the sprockets of adjacent spindles overlapping, drive sprocket means of larger diameter than the spindle sprockets positioned at one end of the series, and idler sprocket means of larger diameter than the spindle sprockets positioned at the other end of the series, endless chain means extending around the larger sprockets and having its upper run resting on the tops of the driven sprockets, and its lower run spaced below the driven sprockets, and a reservoir for oil having its oil level above the bottom of the larger sprockets whereby oil is supplied by the chain and sprocket means to all of the working parts.

2. Skein winding apparatus including a plurality of closely spaced spindles, each adapted to have one end of a skein secured thereto, a sprocket on each spindle with the sprockets of adjacent spindles overlapping, drive sprocket means of larger diameter than the spindle sprockets positioned at one end of the series, and

idler sprocket means of larger diameter than the spindle sprockets positioned at the other end of the series, endless chain means extending around the larger sprockets and having its upper run resting on the tops of the driven sprockets, and its lower run spaced below the driven sprockets, a guard bar normally out of contact with the chain but positioned close enough above its upper run to prevent the chain means from jumping off of the spindle sprockets under abnormal conditions.

3. Skein winding apparatus including a plurality of closely spaced spindles, each adapted to have one end of a skein secured thereto, a sprocket on each spindle with the sprockets of adjacent spindles overlapping, drive sprocket means of larger diameter than the spindle sprockets positioned at one end of the series, and idler sprocket means of larger diameter than the spindle sprockets positioned at the other end of the series, endless chain means extending around the larger sprockets and having its upper run resting on the tops of the driven sprockets, and its lower run spaced below the driven sprockets.

4. A skein winding apparatus including a plurality of spindles each adapted to have a skein attached thereto, a small sprocket on each spindle, chain means having one run resting on the sprockets and one run spaced therebelow, a driving sprocket around which said chain runs, a shaft for driving said driving sprocket, a worm on the shaft, a gear driven by the worm, a second worm connected to the gear through a universal joint, means for moving the second worm between two positions, a gear driven by the second worm in one position thereof, a switch and a latch controlled by said last-named gear, a motor controlled by the switch for driving the entire system, said latch maintaining the worm moving means in engaged position.

5. A counter comprising a counting wheel, means for biasing the wheel in one direction and an adjustable stop for limiting its movement in this direction to provide a variable starting position, a drive member, a gear driven by the drive member through a universal joint and movable between engaged and disengaged positions in the first of which it drives the counter wheel, a slide in which said gear is mounted for movement between the two positions, a latch for locking the slide in the engaged position, the slide being biased to the disengaged position, a handle for raising the slide, a motor driving the drive shaft, means operable by the counting wheel when it rotates to a predetermined position for releasing the latch, and a switch controlled by said slide to connect said motor when in said engaged position and disconnect it when in the disengaged position.

6. A control meter comprising a counting wheel, means for biasing the wheel in one direction and an adjustable stop for limiting its movement in this direction to provide a variable starting position, a drive member, a gear connected to the drive member through a universal joint and movable between engaged and disengaged positions in the first of which it drives the counter wheel, a shiftable member on which said gear is mounted for movement between the two positions, a latch for locking the shiftable member in the engaged position, the shiftable member being biased to the disengaged position and manually operable to the other direction, and means operable by the count-

ing wheel when it reaches a predetermined position for releasing the latch.

7. A control meter comprising a counting wheel, means for biasing the wheel in one direction and an adjustable stop for limiting its movement in this direction to provide a variable starting position, a drive member, a gear connected to the drive member through a universal joint and movable between engaged and disengaged positions in the first of which it drives the counter wheel, a 10 shiftable member on which said gear is mounted for movement between the two positions, a latch for locking the shiftable member in the engaged position, the shiftable member being biased to the disengaged position and manually operable to the other direction, means operated by the shiftable member for controlling the operation of associated mechanism, and means operable by the counting wheel when it reaches a predetermined position for releasing the latch.

8. Material treating apparatus including a plurality of closely spaced generally horizontal spindles, each adapted to have material secured thereto, a sprocket on each spindle with the sprockets of adjacent spindles overlapping, drive sprocket means of larger diameter than the spindle sprockets positioned at one end of the series, and idler sprocket means of larger diameter than the spindle sprockets positioned at the other end of the series, endless chain means extending around the larger sprockets and having its upper run resting by gravity on the tops of the driven sprockets, and its lower run spaced below the driven sprockets, a guard bar normally out of contact with the chain but positioned close enough above its upper run to prevent the chain means from jumping off of the spindle sprockets under abnormal conditions.

9. Skein winding apparatus including a plurality of closely spaced spindles, each adapted to have one end of a skein secured thereto, a sprocket on each spindle with the sprockets of adjacent spindles overlapping, drive sprocket means of larger diameter than the spindle sprockets positioned at one end of the series, and idler sprocket

10
15
20
2530
35

means of larger diameter than the spindle sprockets positioned at the other end of the series, endless chain means extending around the larger sprockets and having a first run resting on the driven sprockets and biased to this position other than mechanically, and its other run spaced from the driven sprockets, a guard bar normally out of contact with the chain but positioned close enough to its first run to prevent the chain means from jumping off of the spindle sprockets under abnormal conditions.

10. Material treating apparatus including a plurality of closely spaced spindles, each adapted to have material secured thereto, a sprocket on each spindle with the sprockets of adjacent spindles overlapping, drive sprocket means of larger diameter than the spindle sprockets positioned at one end of the series, and idler sprocket means of larger diameter than the spindle sprockets positioned at the other end of the series, endless chain means extending around the larger sprockets and having its first run resting on the tops of the driven sprockets and biased to this position other than mechanically, and its lower run spaced below the driven sprockets.

11. A control meter comprising a counting wheel, means for biasing the wheel in one direction and an adjustable stop for limiting its movement in this direction to provide a variable starting position, a drive member, a gear connected to the drive member through means maintaining the connection as the gear is shifted and movable between engaged and disengaged positions in the first of which it drives the counter wheel, a shiftable member on which said gear is mounted for movement between the two positions, a latch for locking the shiftable member in the engaged position, the shiftable member being biased to the disengaged position and manually operable to the other direction, means operated by the shiftable member for controlling the operation of associated mechanism, and means operable by the counting wheel when it reaches a predetermined position for releasing the latch.

FELIX LANGE.
